UNITED STATES PATENT OFFICE.

FRANK E. MASON, OF McCUNE, KANSAS.

LETTER OPENER.

Application filed November 17, 1926. Serial No. 148,910.

This invention relates to a device for cutting off a small portion at the end of an envelope in the opening thereof to gain access to the contents and supplies an article which is both ornamental and adapted for use as a paper weight.

The invention also provides a device of the nature aforesaid embodying a few number of parts, and including a cutting mechanism comprising blades and means yieldably pressing the blades together to insure their positive action at all times in the opening of a letter or the cutting of paper or other material between the blades.

While the drawings illustrate a preferred embodiment of the invention, it is to be understood that in adapting the means to meet specific needs and requirements, the design may be varied and such other changes in the minor details of construction may be resorted to within the scope of the invention as claimed, without departing from the spirit thereof.

For a full understanding of the invention and the merits thereof, reference is to be had to the following description and the drawings hereto attached, in which,

Figure 1 is a perspective view of a letter opener embodying the invention.

Figure 2 is a vertical longitudinal sectional view of the device.

Figure 3 is a vertical transverse sectional view on the line 3—3 of Figure 2, looking to the left as designated by the arrows.

Figure 4 is a view similar to Figure 3 taken on the line 4—4 of Figure 2, looking to the right, as indicated by the arrows.

Corresponding and like parts are referred to in the following description and designated in the several views of the drawings by like reference characters.

The device comprises a hollow body or casing 10, which is elongated and open at the bottom and front, said casing preferably consisting of a casting, which is oblong, or elongated and formed centrally of the top with an opening from which depends a boss 11, in which is mounted a stem 12. A knob or head 13 surmounts the upper projecting end of the stem 12 and the latter has a slot 14 formed in its lower end to receive the upper portion of a pivoted blade 15 and a roller 16 which is mounted upon a pin 17, whose ends project to engage the lower end of the boss 11 and thereby limit the upward movement of the stem 12. The pin 17 thus

forms an axis for the roller 16 and stops to limit the upward movement of the stem and prevent its displacement. Lugs 18 project inwardly from the ends and front of the casing and are disposed at opposite sides of the front opening and are utilized as supporting means for the working parts. Knobs 19 of rubber or other suitable material are provided upon the bottom side of the casing adjacent the corners and prevent marring the finish of a desk or table upon which the device may be placed. These knobs also prevent noise when placing the article upon a table or other supporting surface. The opening in the front of the casing is covered by an upper plate 20 and a lower plate 21 which are removable to facilitate access to the interior of the casing for assembling and adjusting the parts. The lower plate 21 terminates in the plane of the fixed blade 22 and has an inwardly disposed lip 23 which provides a rest and support for the end of the envelope or other article placed in position to have a portion cut therefrom. The fixed blade 22 is attached at its ends to the lugs 18, by machine screws 24 or like fastening means. The top sides of the blade 22 and the lip 23 are in the same plane and provide a rest or support for the article to be cut. The upper plate 20 has a portion of its lower edge bent inwardly, as indicated at 25, to assist materially in directing the envelope or other article when introducing the same into the device to be cut. A space is provided between the top side of the lip 23 and the lower edge of the inwardly deflected portion 25 and this space constitutes the letter receiving opening.

The pivoted blade 15 is fast at its pivotal end to an upstanding loop 26 of a yoke 27 which is pivoted to a companion yoke 28 secured to one of the lugs 18. The yokes 27 and 28 are oppositely disposed and are pivotally connected by means of a pin 29 passing through overlapping portions of the yokes. A coil spring 30 is mounted upon the pin 29 and normally exerts a pressure to move the yoke 27 and the blade 15 carried by said yoke towards the fixed blade 22, whereby to maintain the cutting edges of the two blades in close contact for positive and effective operation. An arm 31 depends from the heel or pivotal end of the blade 15 and a coil spring 32 connects said arm with the lug 18 at the opposite end of the casing, whereby to hold the free end of the pivoted blade

elevated, as indicated most clearly in Figure 2. The coil spring 32 is disposed below the fixed blade 22 and is protected thereby and the tension of the spring is such as to hold 5 the stem 12 elevated.

Means are provided for limiting the introduction of the article when placing it in position to be cut. The means embodies guards 33 and 34 which are disposed at 10 opposite ends of the casing. The guard 33 consists of a plate which is attached to the rear side of the pivoted blade 15 adjacent its pivotal end. The guard 34 also consists of a plate which is connected to the lug 13 15 by the same fastening 24 employed for connecting the spring 32 to the lug. The guard member 33 projects below the fixed blade 22 and moves with the pivoted blade 15. The fixed guard 34 projects upwardly above the 20 blade 22. Both guards are spaced inwardly from the cutting edge of the blade 22 a determinate distance to admit of a small portion being cut from the end of an envelope when the same is placed in position to be 25 opened.

The article besides being useful as a letter opener serves as a paper weight and it is an ornament to the desk or table. The envelope to be opened is placed with an end upon the 30 lip 23 and is moved across said lip and the blade 22 until arrested by coming in contact with the guards 33 and 34. A sharp blow upon the head of the stem 12 depresses the same and operates the pivoted blade 15, 35 which in conjunction with the blade 22 severs the end of the envelope projecting beyond the cutting edge of the blade 22, the cutting dropping into the lower portion of the casing.

Having thus described the invention, I 40 claim:

1. A letter opener comprising a casing having an opening in its top, fixed and pivoted blades within the casing, a spring normally 45 holding the pivoted blade spaced from the fixed blade, a stem movably mounted in the top opening of the casing and having its lower end slotted to receive the upper edge portion of the pivoted blade, and a roller 50 within the slot of the stem and in contact with the upper edge of the pivoted blade.

2. A device of the character specified comprising a casing having an opening in its top and having a boss in line with the opening, fixed and pivoted blades within the 55 casing, a spring coacting with the pivoted blade to normally hold it spaced from the fixed blade, a stem mounted in the opening and boss at the top of the casing and having its lower end slotted to receive the upper 60 edge portion of the pivoted blade, a roller within the slot of the stem and a pin supporting the roller and projecting to form a stop to limit the upward movement of the stem.

3. In a device of the character specified, a casing, fixed and pivoted blades within the casing, a guard carried by the pivoted blade and extending across the fixed blade and a second guard projecting across the fixed 70 blade and acting with the movable guard to limit the introduction of the article to be cut when placing it in position.

4. In a device of the character specified, a casing having an article receiving opening in a side and inwardly disposed lugs at opposite sides of the said opening, a fixed blade secured to the lugs, a yoke mounted upon one of the lugs, a reversely disposed yoke pivoted to the before mentioned yoke 80 and having an upstanding loop, a pivoted blade secured to the upstanding loop, and a spring associated with the yokes and operating to press the pivoted blade laterally towards the fixed blade.

5. In a device of the character specified, a casing having an article receiving opening in a side and inwardly disposed lugs at opposite sides of the said opening, a fixed blade secured to the lugs, a pivoted blade 90 mounted upon one of the said lugs and having a depending arm, a contractile spring disposed below the fixed blade and connecting the depending arm of the pivoted blade with the other lug, a guard attached to the last mentioned lug and projecting above the fixed blade, and a guard depending from the pivoted blade and projecting below the fixed blade.

In testimony whereof I affix my signature.

FRANK E. MASON. [t. s.]
